ASSIGNORS TO THE PHILADELPHIA TEXTILE MACHINERY COMPANY, OF PHILA-
DELPHIA, PENNSYLVANIA, A CORPORATION OF PENNSYLVANIA.

DRYING-MACHINE.

1,161,732.

Specification of Letters Patent. Patented Nov. 23, 1915.

Application filed August 11, 1914. Serial No. 856,274.

To all whom it may concern:

Be it known that we, WILLIAM H. RIHL and ELWOOD B. AYRES, citizens of the United States, and residents of Philadelphia, county 5 of Philadelphia, State of Pennsylvania, have invented certain Improvements in Drying-Machines, of which the following is a specification.

Our invention relates to certain improvements in drying machines of the type in which the material is conveyed through a chamber and is subjected to the action of heated air, which is circulated through the chamber.

This invention is particularly adapted for drying leather board, although it will be understood that it can be used for drying pottery, bricks, and other material, in which the moisture is to be slowly removed from 20 the articles.

One object of the present invention is to design the drier so that the moisture is slowly extracted from the material during the first steps in the drying operation by 25 currents of air passing transversely from one side of the drier to the other and through the layers of the material being dried.

A further object of the invention is to 30 provide means for completely drying the material after the excess moisture has been removed.

A still further object of the invention is to remove the moisture at given intervals by 35 the proper circulation of air from one side of the drier to the other.

In the accompanying drawings:—Figure 1^a, is a side view of one half of our improved drier; Fig. 1^b, is a side view of the 40 other half of the drier; Fig. 2^a, is a plan view, partly in section, of part of the drier illustrated in Fig. 1^a; Fig. 2^b, is a plan view of part of the drier illustrated in Fig. 1^b; Fig. 3, is a transverse sectional view of the 45 drier on the line c—c, Fig. 1^a; Fig. 4, is a side view of one of the trucks, which is used when leather board, or similar material, is being dried; Fig. 5, is an end view of one 50 of the trucks; and Fig. 6, is a longitudinal sectional view of one of the trays which is mounted on the truck.

Referring to the drawings, 1 is the casing of the drier, which has three longitudinal compartments 2, 2 and 3, separated by lon-

gitudinal partitions 4, as illustrated in Fig. 55 3. In the two side compartments are coils of heating pipes 5. These coils are made in sections throughout the entire length of the machine and the sections are spaced apart to allow for the location of the driving 60 shafts for the several fans. It will be noticed that the pipes on one side are staggered with respect to the pipes on the other side. The partitions 4 are, in fact, a series of spaced sections, in which are circular 65 openings for the fans 6. The fan openings of one partition are opposite spaces 8 in the other partition, so that the air is free to circulate across the drying chamber due to the action of the several fans. The fans 6 70 are mounted on short horizontal shafts 7 mounted in bearings on the frame of the drier and may be driven by power in any suitable manner. In the first portion of the apparatus there is no inlet opening for 75 air from the outside, so that the moist heated air is retained in the first portion of the drier in order to prevent the rapid drying of the material, as better results are attained if it is not quickly dried. 80

In the present instance there are three outlet ducts 9, 11 and 13, spaced a certain distance apart according to the material being dried. In the first duct 9 is an exhaust fan 10 and in the second duct 11 is an 85 exhaust fan 12, and in the third duct 13 is an exhaust fan 14. All these fans are power driven, preferably in the manner shown in Fig. 1^a.

In the drying chamber 3 of the apparatus 90 are tracks 15. 16, 16 are trucks having wheels 17 adapted to the tracks. In the present instance, there are two tracks located side by side as the trucks are comparatively narrow, but it will be understood 95 that a single track may be used in some instances, extending the full width of the drying chamber. On each truck is a frame 18 having rails 19 spaced a given distance apart to receive trays 20, which are perforated and are so arranged that each tray will properly support a sheet of leather board, or other material. When the trays are assembled there is a clear space between each tray so that the warm and hot air will 100 pass in between the trays, thoroughly heating and drying the material carried thereby.

The construction illustrated in Figs. 4

and 5, we prefer to use in drying sheet material, but where bulk material, such as bricks, drain pipes, and the like, are to be dried we preferably use trucks without the 5 framework.

In operating our improved drier, the leather board, for instance, is fed into the machine at the end marked *x*, and the air circulates through the layers of the board, 10 heating the board and removing therefrom a certain proportion of the moisture. This moisture is not allowed to escape immediately, but circulates for a certain length of time until it escapes through the first outlet 15 duct 9 in the roof. The inlet of fresh air being only at the discharge end of the machine, and this air makes its way through the machine toward the inlet end so as to prevent moist air circulating at the discharge end. A portion of this air, after it takes up the moisture, escapes through the third outlet duct 13 and a portion, with additional moisture, escapes through the second duct 11, and the remainder escapes 20 through the first duct 9, as described above. Consequently, the material is subjected, during the first portion of the treatment, to heated moist air, then the moisture is gradually decreased so that when the material 25 reaches the outlet end of the apparatus it is free of moisture and dry. This method of drying prevents the leather board, plastic and like material from warping or cracking, due to the rapid removal of moisture.

35 We claim:—

1. The combination in a drier, of a casing; two longitudinal partitions in the casing forming three compartments, the central compartment being the drying chamber 40 and the side compartments being the heating chambers; a series of heating pipes in the heating chambers, each partition having a series of fan openings, the openings in one partition being out of line with the fan 45 openings in the other partition; power driven fans mounted in the openings; a series of exhaust ducts communicating with the chambers some distance from the feed end of the drier; and an exhaust fan in each 50 duct so as to draw a certain amount of moist air from the drying chamber.

2. The combination in a drier, of a casing; two longitudinal partitions therein forming three longitudinal chambers, the 55 central chamber being the drying chamber and extending from one end of the casing to

the other; tracks in said chamber; trucks arranged to travel on said tracks and to carry the material to be dried; heating pipes in the side chambers; a series of fan openings in the longitudinal partitions, the fan 60 openings in one partition being out of line with those in the other partition; a power driven fan in each opening; an inlet for fresh air at the discharge end of the drier; an exhaust duct communicating with the 65 interior of the drier near the center; and two exhaust ducts communicating with the interior of the drier, one of said ducts being spaced a distance from the first mentioned 70 duct and the other duct being comparatively close to the last mentioned duct, so that the moist air is removed from the apparatus after it has been retained a given length of time and prior to the final removal of the 75 material from the drier, so that the material under treatment will be slowly dried with a certain amount of moisture retained therein during the first part of the operation, the remainder of the moist air being 80 removed prior to the final drying with the hot air.

3. The combination in a drier, of a casing having two longitudinal partitions therein forming a central drying chamber and two 85 side heating chambers; a series of sections of heating pipes in the side chambers and spaced apart, each longitudinal partition having a series of fan openings, the fan 90 openings in one partition being out of line with those of the other partition; a series of transverse fan shafts; fans on the shafts mounted in the fan openings in the partitions, the fan shafts being located in the space between the sections of the heating 95 pipes; a series of exhaust ducts communicating with the upper portion of the drying chamber and spaced apart and located near the discharge end of the apparatus, so that the drying air will retain a certain amount 100 of moisture during the first part of the drying operation, but during the latter part of the drying operation the air will be free from moisture.

In testimony whereof, we have signed our 105 names to this specification, in the presence of two subscribing witnesses.
